UNITED STATES PATENT OFFICE.

LOUIS B. GIRARD, OF LOS ANGELES, CALIFORNIA, ASSIGNOR TO COLUMBIA MILLS INCORPORATED, OF NEW YORK, N. Y., A CORPORATION OF NEW YORK.

FRAME FOR STRETCHING SHADE CLOTH.

Application filed April 22, 1925. Serial No. 26,424.

To all whom it may concern:

Be it known that I, LOUIS B. GIRARD, a citizen of the United States, residing at Los Angeles, county of Los Angeles, State of California, have invented a new and useful Improvement in Frames for Stretching Shade Cloth, of which the following is a specification.

This invention relates to frames for stretching shade cloth or other fabric or for holding it in place while it is being painted, sized, or dried, and particularly to frames for this purpose in which the upper and lower rails are wholly of metal. The frames used for this purpose are ordinarily made in sections and it is necessary to pivotally secure one of the rails and preferably the lower rail of each section to the corresponding rail of adjacent section or sections, so as to permit such rail to be spread away from the other rail at such points of connection between adjacent sections so as to stretch the cloth. The main object of the present invention is to provide a novel means for securing or connecting adjacent rail sections together so as to permit relative angular displacement of said sections to stretch the cloth but to limit the amount of such angular displacement so that in the event of accidental release of the means normally holding the lower rail in suspended position the extent to which the rail sections may fall due to the pivotal connection between the same is limited so as to prevent tearing of the cloth or damaging of parts of the frame by striking one another as would be apt to occur otherwise as herein-after described. With this object in view the invention comprises in connection with a stretching frame of the above type, a rail formed of sections placed end to end, and means for non-rigidly connecting said sections together so as to permit the normal amount of angular displacement between said sections as required in moving the same for stretching the cloth, but to limit the maximum angular displacement which may occur between the adjacent sections of the rail.

The accompanying drawings illustrate embodiments of my invention and referring thereto;

Fig. 1 is a front elevation of a section of a cloth stretching frame whose lower rail

sections are provided with connecting means according to my invention.

Fig. 2 is a vertical transverse section of the upper and lower rails of the frame on line 2—2 in Fig. 1.

Fig. 3 is a partial rear elevation of adjacent lower rail sections and the connecting means therefor.

Fig. 4 is a sectional view of the connecting means on line 4—4 in Fig. 5.

Fig. 5 is a section on line 5—5 in Fig. 3.

The frame shown in Fig. 1 comprises upper rails and lower rails connected by suitable stretching bars as hereinafter described, said rails being in general made in a series of sections which are connected end to end so as to provide for holding and stretching a relatively long piece of shade cloth or other fabric. The construction of one section of such a frame with a portion of the adjoining section is shown in Fig. 1, with parts broken away as indicated and it will be understood that all the sections throughout the frame are of substantially the same construction. Such frame section comprises an upper rail 1 and a lower rail 2, said rails being of similar construction but in relatively inverted position as shown in Fig. 2. Each rail comprises a main rail member formed as a flanged metal rail for example a channel iron as indicated at 3, and a fixed clamp member or clamp plate member 4 formed for example of a strip of sheet metal so as to give the required rigidity, said clamp plate being permanently and rigidly secured to the rail member 3 by suitable means for example by rivets, indicated at 5, and projecting vertically from the rail member so as to provide a relatively thin member for attachment of the cloth. Each clamp plate 4 is provided at its outer or free edge, that is to say at the lower edge of the upper clamp plate and the upper edge of the lower clamp plate, with a flange or turned over portion 6 forming a groove 7 cooperating with movable clamp means as hereinafter described to secure the shade cloth on the clamp member 4. Said movable clamp means is herein shown as being of the same construction as that shown in patent to L. B. Girard, No. 1,371,417, issued March 15, 1921, but it may be of any other suitable or well-known construction, the construction shown comprising movable clamp

105

- plates 8 having hinged connections 9 for arms or straps 10 which are pivoted or hinged at 11 to plates 12, secured to the rail members 3, for example by rivets or bolts 13 extending through said members 12, 4, and 3. The upper rails of adjacent sections may be secured together for example by a fish plate or tie plate 19 and bolts 20 passing through said fish plate and said rail sections. 10 The upper fixed clamp plate members 4 of the adjacent sections may also be secured together for example by means of straps and rivets. The manner of securing the upper rail sections together is relatively unimportant however, and forms no part of this invention, as any other suitable means for rigidly connecting the sections together may be employed.
- The adjacent sections of the lower rails, 20 however, are joined together according to my invention by non-rigid connecting means adapted to permit a limited amount of angular displacement of said sections relative to one another. For this purpose a pair of 25 fish plates or tie plates 15 may be provided, extending across the joint between the sections as at 16, and one in front and one behind the rail members, as shown in Figs. 2 and 5. Said fish plates may be rigidly secured to one of the rail sections 3 for example by means of bolts 17 passing through holes in said fish plates and in the rail section 3 and the fixed clamp plate 4 and provided with nuts 21. The fish plates are 30 pivotally or non-rigidly secured to the other rail section for example by means of a bolt 18 passing therethrough and preferably provided with a pair of lock-nuts or jam nuts 22 to permit tightening of said nuts on the bolt while leaving sufficient play between the fish plates and the rail section to permit turning or angular displacement thereof. Stop means or limit means are provided however, for limiting the maximum angular 45 displacement which may occur, such stop or limit means comprising for example a bolt 40 passing through holes in both fish plates and secured thereto preferably by means of lock nuts or jam nuts 41, and also passing 50 through a recess or notch 42 in rail section 3. Said recess is of somewhat greater width than bolt 40, so as to permit limited angular movement of rail member 3 about pivot bolt 18, but the edges of the recess are adapted 55 to engage said bolt when a certain angular displacement is reached so as to prevent further angular displacement, as hereinafter described.
- Means are provided for forcing or spreading the upper and lower rails apart at the joints of the lower rail after the cloth is secured thereto so as to stretch such cloth. Such means may comprise, for example, spreading arms 24, consisting for example 60 of angle irons and pivotally mounted on the

lower rails members adjacent each joint, for example, as shown, by means of one of the bolts 17 aforesaid or if desired by means of one of the pivot bolts 18, and a lever arm 25 pivotally mounted on the upper rail, for example, by means of U-shaped straps 26 and bolts 27. In order to permit swinging movement of spreading arm 24 about bolt 17 and sufficient lateral movement thereof to facilitate engagement thereof with lever arm 25 as hereinafter described, I prefer to provide a spacing washer 23 surrounding said bolt and extending through and of somewhat greater thickness than said spreading arm, so that nuts 21 may be tightened 70 up on said washer to hold the fish plates rigidly to the rail section while permitting swinging of arm 24. Each of said lever arms is provided with a pin or stud 28 adapted to engage in any one of a plurality of recesses or notches 29 in the corresponding spreading arm 24, so that downward movement of lever arm 25, with said stud engaged in a suitable notch will cause spreading arm 24 to force the upper and lower rails apart at this point. The above described spreading means are such as are commonly used in the art any other suitable or well-known means may be used for this 80 purpose.

The frame may be hung or supported in any suitable manner, for example, by means of wire hangers 30 and eye-bolts 31, said hangers depending for example, from means travelling in suitable ways, to permit the 85 assemblage of a large number of the frames in parallel order and of separation of adjacent frames for access thereto in inserting, painting or removing the cloth.

The rail members of the upper and lower rails may be of any suitable shape or cross-section, but are preferably flanged in order to provide maximum strength and rigidity; for example instead of channel irons, said members may comprise angle irons or T-bars to which the fixed clamp plates 4 are secured in any suitable manner, the remainder of the construction being substantially the same as above described.

In the operation of the stretching frame 115 above described a strip or sheet of window shade cloth or other fabric to be stretched, indicated at 33 is inserted at its upper and lower edges between the moving and fixed members 8 and 4 of the respective clamping 120 means, the movable clamping members 8 being moved to the position indicated in dotted lines at 8' in Fig. 2 to permit insertion of the edges of the fabric within groove 7 after which said movable clamp members 125 are pushed or snapped into the position indicated in full lines in said Fig. 2, so as to engage the edges of the fabric as at 32 and hold the same tightly in place. It will be understood that during the insertion of the 130

cloth within the clamping means in this manner the lower rail 2 may be supported at the proper height in any suitable manner, for example by causing the pin 28 on lever arm 25 to engage in a suitable notch 29 in arm 24 and allowing said arms to rest in a vertical position as shown in dotted lines at 34 in Fig. 1. After the fabric is thus clamped throughout the entire length of the stretching frame the spreading arms are released from engagement and swung to horizontal position, suitable supporting clips indicated at 37 being provided at the back of the respective rails for holding such arms in this position, and the sizing medium, for example a suitable glue and water size, is applied to one or both sides of the fabric by means of a brush or in any other suitable manner.

As soon as the sizing is applied to an entire strip of cloth, the operator begins the stretching operation at one end of the frame. This is done by swinging the arms 24 and 25 to a position to permit the pin 28 to engage in a higher notch 29 than that with which it originally engaged, as indicated at 35 in Fig. 1, and lever arm 25 is then moved downward so as to push the lower frame 2 downward and stretch the fabric. The arms 24 and 25 are therefore commonly known as stretcher bars. In this operation it will be seen that a certain amount of angular displacement occurs between the two adjacent lower rail sections when the same are spread away from the upper rail, this displacement being provided for by the pivotal connections of fish plates 15 to one of the rail members as above described. This operation may be repeated if necessary until the proper amount of stretching is obtained. The rails are then held in this position so as to maintain the fabric in stretched condition by bringing the arms 24 and 25 to vertical position with the pin 28 engaged in a suitable notch 29 and the same stretching operation is then repeated at the next joint between the lower rail sections. The entire strip of fabric is thus stretched and kept in stretched condition by engagement of the stretcher bars until the sizing medium has dried, which may require for example from 8 to 12 hours or longer.

When the entire strip of fabric has been sized, stretched, and dried in this manner, the stretcher bars may again be released and allowed to rest on supports 37, as the sized cloth will then retain its stretched condition, assisted only by the weight of the lower rail. The paint to be used may then be applied to both sides thereof in the usual manner, for example by means of an ordinary brush. The paint is then allowed to dry upon the cloth, such drying requiring for example from 12 to 24 hours, depending upon the humidity of the surrounding air, and the

sized and painted cloth is then removed from the frames. To permit such removal of the cloth the movable clamping members are again opened or moved to the position indicated at 8', such opening operation being easily performed for example by inserting a pointed tool or rod under the edges of the clamps 8 or the straps 10 or hinges 9 and prying the same outward past the dead center position. Or if desired the main strip of cloth may be removed by cutting along the edges next to the clamps, and the remaining edge portions of the cloth then removed from the clamps.

It may occasionally occur that when the frame is empty, or when the cloth or fabric is being clamped thereto or removed therefrom, the engagement between a pair of stretcher bars may accidentally be broken due to the pin 28 slipping out of the notch 29 in which it is engaged, or such engagement may be intentionally broken for some purpose. The adjacent rail sections will therefore be unsupported at this point and will begin to fall. The stop or limit means above described will then function, however, to arrest the falling motion of the rail sections, by engagement of bolt 40 with the upper edge of the recess 42, thus holding the parts in the position indicated in dotted lines at 43 in Fig. 4. It will be observed that when the parts are in this position the upper corners 44 of the two adjacent fixed clamp plates 4 have not yet hit each other, and an important advantage of the stop means is that they prevent such hitting of these corners, which would occur if the rail sections were allowed to fall freely, and which has been found in practice, without the use of stop means, to badly damage these corners and bend the relatively thin sheet metal of which the fixed clamps are formed, so that they must be straightened or repaired before using again in order to permit engagement of the hinged clamp means therewith or to avoid tearing the cloth at this point. Furthermore, if the cloth is being inserted or removed from the frame, and the accidental or intentional release of the stretcher bars occurs at a joint between sections which is say, less than one section away from the nearest point at which the cloth is clamped to the frame, the dropping of the lower frame member for a great distance may cause tearing of the cloth adjacent the nearest point of attachment to the frame, and this is also prevented by the above-described stop or limit means.

What I claim is:

1. In a cloth stretching frame a rail comprising a plurality of sections placed end to end, connecting means rigidly secured to one of said sections adjacent the end thereof, means non-rigidly securing said connecting means to the adjacent section so as to per-

- mit relative angular displacement between said sections and stop means on said connecting means and on the section to which it is nonrigidly connected adapted to cooperate to limit such relative angular displacement.
2. In a cloth stretching frame, a connecting means for adjacent rail sections, comprising means extending across the joint between such rail sections and adapted to be secured thereto, means for rigidly securing said connecting means to one of said sections, means for nonrigidly securing said connecting means to the adjacent section, and stop means secured to said connecting means and adapted to cooperate with means on the rail section to which it is non-rigidly secured to limit the relative angular displacement between such sections.
- 10 3. A cloth stretching frame comprising an upper frame and a lower frame, said lower frame comprising a plurality of sections, connecting means for said sections of the lower rail, said connecting means being rigidly secured to one of said rail sections and being non-rigidly secured to an adjacent rail section so as to permit relative angular displacement between said sections, spreading means comprising a member hingedly secured to one of said sections adjacent said connecting means and a member
- 15 hingedly secured to the upper rail and adapted to engage with said first-named spreading member to spread the rails at this point and thus cause relative angular displacement between said sections of the lower rail, and stop means on said connecting means and on the rail section to which said connecting means are non-rigidly secured adapted to cooperate to limit the relative angular displacement between such rail sections.
- 20 4. In a cloth stretching frame a rail comprising a plurality of sections placed end to end, connecting means extending across a joint between adjacent sections, means rigidly securing said connecting means to one of said sections, means non-rigidly securing said connecting means to the adjacent section and a transverse member connected to said connecting means and passing through said recess, said recess being larger than said transverse member so as to permit relative angular displacement between said rail sections but adapted to engage such transverse member so as to limit such displacement.
- 25 In testimony whereof I have hereunto subscribed my name this 22nd day of April 1925.

LOUIS B. GIRARD.
